UNITED STATES PATENT OFFICE.

JOSEPH SACHS, OF HARTFORD, CONNECTICUT.

MAGAZINE SCREW-PLUG FUSE.

Application filed February 26, 1923. Serial No. 621,257.

To all whom it may concern:

Be it known that I, JOSEPH SACHS, a citizen of the United States, residing at Hartford, in the county of Hartford and State of Connecticut, have invented a new and useful Improvement in Magazine Screw-Plug Fuses, of which the following is a specification.

This invention relates to those screw plug fuses which have a plurality of fusible elements so arranged that when an element is blown another element can be immediately substituted in the circuit which the device is designed to protect.

15 The object of the invention is to provide a device of this character which has a magazine carrying a plurality of fusible elements that is simple and cheap to manufacture and which is so designed that when 20 a fuse is blown the circuit may be quickly restored by merely withdrawing the magazine from the screw shell and then putting it back in a new relation.

This object is attained by attaching to the 25 metallic shell which is designed to screw into the common socket or base receptacle, a conducting contact, and providing a magazine shaped to be inserted into the screw shell, which magazine carries a plurality of 30 fusible elements that have their outer ends connected to a common center contact and have their inner ends separated and each adapted to register with and be engaged with the shell contact according to the 35 rotational relation of the magazine and the shell when the magazine is thrust into the shell. In other words when the magazine is thrust into the shell one of the fusible elements engages the shell contact and closes the circuit through the plug. When that fuse is 40 blown the magazine is withdrawn from the shell, turned a little and then thrust back into the shell so that another fuse engages the shell contact and completes the circuit.

45 This can be repeated until all of the fuses carried by the magazine are blown, and then if desired the magazine may be re-loaded with fusible elements.

In the accompanying drawings Figure 1 50 shows a central longitudinal section of one form of device that embodies the invention. Fig. 2 shows a view of one end of a five link removable magazine, with three fusible strips in operative position, two of the strip paths being unoccupied. Fig. 3 is a side view of the magazine. Fig. 4 is a view of

the outer end of the magazine with three fusible elements and with the center contact omitted. Fig. 5 shows a bottom view of the assembled device illustrated in Fig. 1. Fig. 6 is a longitudinal section of a modified design. Fig. 7 is a transverse section on plane indicated by the dotted line 7-7 on Fig. 6. Fig. 8 is a plan of the center contact of the magazine shown in Fig. 6. Fig. 9 is a side elevation, with part broken away, of a magazine with a different form of center contact. Fig. 10 is a plan of the center contact shown in Fig. 9.

The base 1 of the plug is desirably made 70 of porcelain and the metallic screw shell 2 has one end molded therein. To the inner wall on one side of the screw shell is fastened a contact 3 of conducting material. This contact is illustrated as a spring finger 75 with its outer end fastened to the shell by a rivet 4 and its inner end free to yield radially of the shell. The outer end of the finger may be fastened near the outer end of the shell as shown in Fig. 1, or further 80 in as shown in Fig. 6.

The magazine 5 is desirably made of porcelain of a maximum diameter that will snugly fit in the screw shell. In the designs of magazine illustrated there are five 85 grooves 6 extending longitudinally in the outer wall and five passages 7 extending through the magazine from end to end and communicating with the grooves. The grooves may extend the entire length of the 90 outer wall of the magazine as shown in Fig. 3, or only part way as shown in Fig. 9. The number of these strip paths may obviously be varied.

The fusible elements are of common material and capacity, those shown being in the form of metallic strips 8. These strips are thrust through the passages and the inner ends 9 are folded over the edge of the inner end of the magazine so as to lie isolated from each other in the grooves on the exterior. The outer ends 10 of the strips may as shown in Fig. 1, be bent over the outer end of the magazine and be held in place by the flange 11 of a metallic cap 12 105 which forms the center contact of the plug. This cap may be secured in place in any desired manner, as by screw 13.

In the form shown in Fig. 9 the outer ends 14 of the fusible strips are bent over 110 the end of the magazine and held in place by a metallic cap 15 which has fingers 16

that extend into the strip passages through the magazine. This cap may be retained in place by the fingers and also by a cementing compound 17 molded into the end 5 of the magazine around the cap. The ends 18 of the fusible strip may be bent over on the inside of the outer end of the cap as shown in Fig. 6.

In this case a metallic spider 19 with a 10 threaded perforation 20 may be used to hold the ends of the strip and make the necessary electrical connection with them, the spider being drawn to place so as to clamp the strip ends by a screw 21 which forms the outside 15 center terminal of the plug. To isolate the passages for the strips an insulating tube 22 may be inserted into the central bore of the magazine as illustrated in Figs. 6 and 7.

The outer ends of all of the fusible elements 20 are electrically connected with the center contact, while the inner ends of the fusible elements are isolated in the grooves 25 in position to be engaged, one at a time, with the contact finger when the magazine is thrust into the shell. When the fusible 30 element that electrically connects the contact finger attached to the shell with the center contact and closes the circuit through the plug, is disrupted by an excess flow of current, the magazine is pulled out of the shell, partially rotated and then pushed back 35 into the shell so that one of the fusible elements that remains complete will reestablish the circuit. In the forms shown the shell contact is substantially the shape of the 40 grooves in the exterior of the magazine so that it forms a guiding key when the magazine is inserted into the shell as well as making contact with the end of one of the fusible elements carried by the magazine. After 45 all of the fusible elements have been blown the magazine may be re-fused by removing the common end contact, inserting fresh strips, bending the ends of the strip and then replacing the cap or end contact. The 50 passages in the magazine for the fusible links may be varied in shape and number as desired, and the shape of the shell contact and the manner of connecting the contact with the shell may be changed as is apparent, without departing from the invention.

The invention claimed is:

1. A fuse plug having an insulating base, a metallic screw shell with its inner end embedded in the base, a metallic spring finger having its outer end electrically attached to the outer end of the screw shell, said finger extending into and adapted to yield radially

within the shell, and an insulating block 60 shaped to fit within and movable longitudinally into and out of the shell, said block carrying a plurality of fusible elements that are joined at their outer ends to a common center contact on the block and that have their inner ends adapted to be engaged one at 65 a time by said finger.

2. A fuse plug having an insulating base, a metallic screw shell with its inner end embedded in the base, an insulating block 70 movable longitudinally into and out of the shell, a plurality of fusible elements extending through the block, said elements having their outer ends joined to a common contact 75 on the block and that have their inner ends bent over the inner end of the block to the outer surface of the block, and a metallic spring finger having its outer end electrically attached to the shell and its inner end bearing radially with a yielding pressure 80 against the end of one of the fusible elements.

3. A fuse plug having a metallic screw shell, an insulating cylinder shaped to fit 85 within the shell, said cylinder having longitudinal grooves in its surface, a plurality of fusible elements that are joined at their outer ends to a common contact and that have their inner ends bent over the inner edge of the cylinder into said grooves, and a metallic spring finger having its outer end electrically attached to the shell and its inner end extending in one of the grooves in the cylinder wall and bearing radially with a yielding pressure against the bent over end 90 of one of the fusible elements.

4. A fuse plug having an insulating base, a conducting screw shell with its inner end embedded in the base, an insulating block 100 adapted to fit within and movable longitudinally into and out of the shell, said block having a plurality of passages from end to end, fusible elements extending through said passages and having their outer ends bent outward over the outer edge of the block and their inner ends bent outward over the inner edge of the block, a spring finger electrically attached to and extending into the shell and adapted to bear radially of the block and shell with a yielding contact 105 against the inner end of one of the fusible elements, and a flanged cap detachably secured to the center of the block and engaging the outer ends of all of the fusible elements.

JOSEPH SACHS.
